DAMPER FOR FURNACES

Thomas H. Banfield, Portland, Oreg.

Application July 25, 1928. Serial No. 295,310

6 Claims. (Cl. 110—45)

This invention relates generally to coal burning furnaces and particularly to means for regulating the supply of air delivered to the combustion of such furnaces.

5 The main object of this invention is to provide an exceedingly simple and efficient form of damper by means of which the orifice can be easily and accurately varied.

The second object is to provide a damper 10 which will eliminate the tendency of blowing back on the part of the fan as is common when certain types of dampers are employed.

The third object is to so construct the damper 15 that the opening may be varied from the maximum to the minimum diameter by a lever movement, which lever is capable of being held in various semi-fixed positions.

The fourth object is to so construct the damper 20 that a shaft may be passed through the center thereof without interfering with its operation.

These, and other objects, will become more apparent from the specification following as illustrated in the accompanying drawings, in which:

25 Figure 1 is a perspective view showing a typical form of stoker to which this device is attached. Figure 2 is a large front elevation of the damper with parts broken away. Figure 3 is a fragmentary section taken along the line 3—3 in Figure 2. Figure 4 is a detail of the operating ring. Figure 5 is a detail of one blade. Figure 6 is an edge elevation of the blade shown in Figure 5. Figure 7 is a diagrammatic rear view showing one blade in place and showing in dotted lines the position of the same blade for maximum opening. Figure 8 is a section taken along the line 8—8 in Figure 7. Figure 9 is a section taken along the line 9—9 in Figure 7.

Similar numbers of reference refer to similar 40 parts throughout the several views.

Referring in detail to the drawings, there is illustrated the front of a furnace 10 in which is placed a tuyère box 11 to which coal is fed from the hopper 12 through a fuel duct 13 and to 45 which air is fed through an air duct 14 by a fan 15. The speed of the fan on such devices is practically constant and the flow of air through the duct 14 is controlled by restriction. This is ordinarily done by means of a winged damper, 50 but in this instance there is employed an iris damper which consists of a damper frame 16 having a somewhat sloping outer face 17 over which is secured a screen 18 by means of the ring 19 and the screws 20. The damper frame 55 16 is secured to the fan casing 15 by means of

the bolts 21. On the rear or inner side of the damper frame 16 is placed an operating ring 22 provided with holes 23 around its central opening 24. The ring 22 is provided with an operating handle 25 on the rear side of which is 60 placed a spring-urged pawl 26 adapted to engage the notches 27 to the outer rim of the damper frame 16.

The blades 28 of the iris damper are somewhat 65 curved and widened at the end 29 which is provided with a pivot 30 formed from the material in the blade 28 itself. The end 31 is relatively straight and narrow and is provided with a pivot 32, also formed from the material in the blade 28, but on the opposite side of the pivot 30. The 70 pivot 30 on the wide end 29 of each blade 28 is placed in a hole 23, the blades overlapping each other in successive order allowing the pivot 32 of each blade to project rearwardly or toward the fan and well toward the outside of the damper. 75 The cover plate 33 provided with the slotted openings 34 is now placed over the blades, each pivot 32 being held and guided by a respective slot 34. In order to prevent the relatively thin 80 blades 28 from being bent by inrushing air, reinforcing bars 35 are provided, whose bent ends 36 are held by the prongs 37 which are pushed out of the metal in the ring 33 and afterwards bent down upon the bars 35, as shown in Figure 9. The damper frame 16 is provided with a 85 slot 38 whose ends 39 form stops for the lever 25 and limit its rotative movement.

The operation of the damper is as follows: When desiring to permit the maximum amount of air to pass into the fan, the lever 25 is moved 90 toward the left as shown in Figure 2. To decrease this amount it is merely moved in the opposite direction. Provision is made for stopping the lever 25 by means of the pawl 26 to prevent any possibility of a change in the 95 damper settings due to vibrations, and also to assist one in securing a certain damper opening whenever desired, namely, the lever can be set at the first, second, third, fourth or fifth notch, which will always give a definite size of 100 damper opening. While it is possible to practically close the opening entirely, if desired, by merely positioning the slot ends 39 to permit this action, this is not always desirable as in numerous instances a shaft is passed through 105 the damper and by making the stop on the lever the blades can always be held out of contact with the shaft.

The blowing back on the part of the fan is entirely eliminated because the distance from 110

the edge of the iris to the center can be controlled so as to make this radial distance less than the zone of pressure within the fan built up by the blades. With a rose or a shutter damper the radial distance from the center to the far edge of the opening is fixed and cannot be altered by partially closing the damper. Consequently whenever the pressure builds up from the periphery to such far point, the dust will be blown out at the far point while, with the iris damper, the distance of the far point is altered and consequently there is no tendency to blow back because the iris damper forms a positive baffle sufficiently far from the periphery of the fan to enclose the annular zone of pressure.

15 I claim:

1. In an underfeed stoker, a retort, an air duct leading to said retort to supply combustion air, a fan at the entry end of the air duct and discharging air tangentially into the duct, a casing surrounding the fan, communicating with the air duct, and having an intake opening in line with the axis of the fan, and means for restricting the size of the intake opening while keeping the opening constantly concentric with the axis of the fan shaft.
2. The combination with an underfeed stoker of a centrifugal fan delivering combustion air to the fire, a casing for said fan having an axial intake opening, and an iris diafram for closing the intake opening of the fan casing.
3. In combination; a retort, tuyères surrounding the retort, an air duct delivering air to the

tuyères, a fan casing having a substantially circular intake opening and an exit communicating with the air duct, a tangential discharge fan within the fan casing and axially arranged with respect to the intake opening, and means for increasing or decreasing by small amounts the size of the intake opening while maintaining said substantially circular intake opening constantly concentric with the fan shaft.

4. The combination with an underfeed stoker of the type having a feed hopper, a fan, a fan casing surrounding the fan and having an intake opening to admit air axially to the fan, a retort, a fuel duct leading from the hopper to the retort, fuel feeding means for forcing fuel thru said duct from the hopper to the retort, a parallel duct for leading air from the fan to the retort, and a motor for driving the fuel feeding means and the fan, of means for restricting at will the size of the substantially circular intake opening to the fan while maintaining the opening, irrespective of its diameter, constantly concentric with the shaft of the fan.

5. The device of claim 2 in which the last means is a manually operated iris diafram.

6. The device of claim 2 plus means between the fan and the blades of the iris diafram for supporting the blades against pressure from the outside of the diafram and toward the fan, said means engaging a plurality of the blades between their two ends.
